MERCURIC ORE REDUCTION FURNACE

Frank Duncan, Terlingua, Tex.

Application September 11, 1941, Serial No. 410,456

7 Claims. (Cl. 266—20)

This invention relates to a furnace of novel and simple construction through which finely crushed sulphide ores, such as cinnabar, are adapted to flow by gravity, having means for roasting the ore, and means for removing the mercuric fumes, released from the ore by the roasting thereof, from the ore, and for conveying the fumes through the furnace and to an exit passage leading to a condenser.

More particularly, it is an aim of the invention to provide an ore reduction furnace of very simple construction having only one moving part, which part functions for conveying the roasted ore, after the removal of the mercuric fumes therefrom, from the furnace, and also for controlling the rate of flow of the ore through the furnace.

Another aim of the invention is to provide a throat through which the ore passes having superposed baffles over which the ore must flow and which causes the ore to flow, at certain points, in very fine streams so that the ore can be readily heated and subjected to heated air, passing back and forth through the throat, for extracting mercuric fumes from the ore.

Still a further aim of the invention is to provide a furnace having heating means for heating the throat and the ore passing therethrough, and which heating means is separated from the ore by the throat so that the products of combustion from the heating means do not come in contact with the ore to thereby prevent the mercuric fumes from the ore, which are conveyed by heated air to a condenser, from being mixed with carbon monoxide gases from the products of combustion.

A particular advantage of the invention resides in the fact that in spite of the fact that the finely crushed ore is thoroughly dried previous to being admitted into the furnace, the ore will contain a certain amount of moisture that can only be eliminated by heat and which is eliminated by the heating of the ore passing downwardly through the furnace to produce steam which is mixed with the hot ascending air and which has a tendency to prevent the mercuric fumes from condensing on the cooler ore, near the top of the furnace.

Other objects and advantages of the invention will hereinafter become more fully apparent from the following description of the drawings, which illustrate preferred embodiments of the invention, and wherein:

Figure 1 is a longitudinal vertical sectional 50 55

view of a furnace constructed in accordance with the invention,

5 Figure 2 is an enlarged fragmentary longitudinal vertical sectional view of the same, taken substantially along the plane indicated by the line 2—2 of Figure 1.

10 Figure 3 is an enlarged fragmentary vertical sectional view of a portion of the furnace taken substantially along a plane indicated by the line 3—3 of Figure 2.

Figure 4 is an enlarged cross sectional view of the furnace taken substantially along a plane indicated by the line 4—4 of Figure 2.

15 Figure 5 is a view similar to Figure 4, showing a slightly modified form of the furnace.

Figure 6 is a fragmentary vertical sectional view of a portion of the furnace, taken substantially along a plane indicated by the line 6—6 of Figure 1, and

20 Figure 7 is a cross sectional view of the furnace taken substantially along a plane indicated by the line 7—7 of Figure 2.

25 Referring more particularly to the drawings, wherein like reference characters designate like or corresponding parts throughout the different views, 10 designates generally a furnace casing formed of a refractory material, such as brick. The furnace casing 10 is elongated, as seen in Figure 1, and is disposed in substantially an upright position and is substantially rectangular in cross section, as seen in Figures 4 and 7, to provide a substantially stack-shaped casing, the lower end 11 of which is enlarged. The furnace casing 10 is provided with a bore 12 in the upper part thereof which extends from the top of the casing 10 into its enlarged bottom portion 11, and the width of which is restricted above the point 13, as seen in Figure 1, for a purpose which will hereinafter become apparent.

30 40 A throat, preferably of metal, designated 14, extends longitudinally through the bore 12 from near its upper end to a point near its lower end. As seen in Figure 2, the bore 12, above the upper end of the throat 14 is tapered to form a bin 15 adapted to receive finely ground ore, not shown.

45 The throat 14, as best seen in Figure 4, is oval-shaped in cross section and the bore 12 is elongated and rectangular in cross section and is provided with longitudinally extending recesses 16 in the edge portions thereof in which the arcuately shaped ends 17 of the throat 14 fit. The sides 18 of the throat 14 are spaced from the side walls 19 of the bore 12. The throat 14 is provided with longitudinally extending walls 20, near its edge portions 17 which divide the throat, lon-

Figure 1 is a longitudinal vertical sectional 50 55

itudinally, into an intermediate chamber 21 and corresponding chambers 22, which chambers 22 are formed by the arcuately shaped edge portions 17 and the walls 20, which are adjacent thereto. As best seen in Figure 2, the bin 15 opens into the upper end of the intermediate chamber 21.

As best seen in Figure 3, the chamber 21 contains a plurality of superposed baffles 23 which are preferably in the shape of an inverted V, in cross section, and each of which is attached at its ends to the walls 20. The upper edge of each baffle 23 is disposed substantially at the same level as the bottom edges of the sides of the baffle 23 thereabove and said bottom edges of the sides of the baffles 23 are spaced from the side walls 18 of the throat 14 to form relatively narrow slots or openings 24 therebetween. As seen in Figures 1 and 3, the walls 20 are provided with the correspondingly disposed openings 25 which open into the cavities 26 formed by the baffles 23 which cavities, combine with the openings 25, which communicate therewith, to form passages between the chambers 22.

As best seen in Figure 2, the chambers 22 are provided with dividing walls 27 which are disposed transversely thereof. One of the chambers 22 is provided with two walls 27, disposed near the ends thereof, and the other chamber 22 is provided with an intermediate wall 27 so that said walls 27 are staggered, for a purpose which will hereinafter become apparent.

The bore 12 is provided with a transverse dividing wall 28 on which the lower end of the throat 13 rests, and which is provided with an elongated opening 29 which communicates with the chamber 21, as seen in Figures 1 and 3, and a restricted opening 30, at one end thereof, which communicates with the lower end of the chamber 22, which contains the two dividing walls 27, as seen in Figure 2.

At substantially the same elevation as the wall 28, the furnace casing 10 is provided with supporting shelves 31 which project outwardly from the opposite sides 32 thereof and through which extend burners 33 of any suitable construction. Above the shelves 31, the sides 32 of the casing 10 are provided with opposed openings 34, as best seen in Figures 1 and 3, which diverge inwardly and which open into the spaces 35 formed by the sides 18 and 19. The burners 33 discharge into the openings 34 and it will thus be readily apparent that the lower portions of the chambers 35 will form fire boxes for receiving the flames, as indicated at 36, from the burners 33 which are directed inwardly through the openings 34 to impinge against the sides 18 of the throat 14 for heating said throat. The upper portions of the spaces 35 form flues and are provided, at their upper ends, with outlet openings 37, as seen in Figure 1, through which the products of combustion can be released from the furnace casing 10 without coming in contact with the interior of the throat 14.

Below the wall 28, the bore 12 is provided with a plurality of pairs of baffles 38. The baffles 38 of each of the pairs thereof are attached to complementary portions of the sides 19 of the lower part of the bore 12 and converge downwardly and inwardly relatively to one another and terminate with their lower, adjacent edges in spaced relationship to one another to form slotted passages 39 therebetween. Each of the pairs of baffles 38 combine to form a hopper, designated generally 40, with the slotted passages 39 forming the outlets thereof, and said hoppers are arranged one

above another and beneath the opening 29 of the plate 28.

The lower portion 11 of the casing 10 is provided with an enlarged hollow interior having an inclined bottom wall 41, said interior forming a container 42 into which the lower end of the bore 12 opens. A hot air heater 43, of any suitable construction is disposed in a portion of the container 42 and is provided, adjacent its bottom, with an air intake pipe 44 which extends from the container 43 outwardly through the casing portion 11 and which is provided, on the outer side of the casing portion 11, with a control valve or damper 45 for limiting the amount of air passing through the pipe 44 and into the heater 43. The upper end of the heater 43 extends into the lower end of the bore 12, adjacent one side 19 thereof and is provided at its upper end with pipes 46 and 47 which project therefrom in opposite directions and toward the narrow side walls 48 of the casing 10, one of said pipes being disposed, at its outer end, adjacent each of the sides 19 of the bore 12. The walls 48 are each provided with two sets of passages, 49 and 50, which connect with the pipes 46 and 47, respectively. All of the passages 49 and 50 have inturned ends which open into the bore 12 and said passages 49 and said passages 50 are staggeredly arranged, as seen in Figures 2 and 6, in the walls 48. The lower end of the lowermost passage 49 is connected to the outlet end of the pipe 46 and the lowermost end of the lower passage 50 is similarly connected to the pipe 47. The remaining ends of the passages 49 and 50, as seen in Figures 1 and 3, open into the bore 12, adjacent the sides 19 thereof and on the outer sides of the baffles 38, and the upper ends of the uppermost passages 49 and 50 open into the bore 12, between the upper hopper 40 and the wall 28. As indicated by the arrows 51 (Figure 6) the hot air from the heater 43 passes through the pipe 46 and the passages 49 and therebetween and on the outer sides of the baffles 38 back and forth through the bore 12 and into the space between the wall 28 and the upper hopper 40. As indicated by the arrows 52, seen in dotted lines in Figure 6, hot air from the heater 43 also passes from the pipe 47 through the passages 50 back and forth through the bore 12 and on the outer sides of the baffles 38, which are disposed adjacent the side 19, opposite to the side adjacent to which the heated air, indicated by the arrows 51, passes. The heated air from the pipe 47, as indicated by the arrows 52, flows in the opposite direction to the heated air indicated by the arrows 51 and is discharged from the upper end of the uppermost passage 50 into the space between the wall 28 and the upper hopper 40, where the air from the passages 49 and 50 intermingle and flow into the chamber 22, containing the two dividing walls 27, through the opening 30.

60 A passage 53 communicates with the restricted bottom of the container 43 and is adapted to have one end, not shown, opening outwardly of the bottom portion 11 of the casing. Passage 53 contains a driven screw conveyor 54, which forms the only moving part of the furnace, and which is adapted to convey the ore, after roasting, away from the furnace. The upper end of the chamber 22, which is provided with the two dividing walls 27, is provided with a pipe leading therefrom outwardly of the furnace casing 10 and which pipe 55 is adapted to be connected to a conventional condenser or condensers, not shown.

65 The bin 15 is adapted to be filled in any conventional manner with finely crushed sulphide

ore, the largest particles of which are preferably less than one-half inch in length between the two most remote points thereof. This finely crushed ore, not shown, flows downwardly from the bin 15 into the chamber 21 and successively over the baffles 23. The ore is discharged from the throat 14 through the openings 25 and passes successively through the hoppers 40 into the container 42 from where the ore is conveyed outwardly through passage 53 by the screw conveyor 54. The parts previously mentioned will be substantially filled with the ore so that the flow of ore through the furnace is governed by the speed at which the conveyor 54 is driven for conveying the ore from the container 42, and said conveyor is adapted to be driven at a speed to cause the ore to pass downwardly very slowly through the furnace. Consequently, the ore passing over each baffle 23 is divided and flows in two fine streams through the slots 24. After the ore passes each slot 24 it spreads out at the enlarged part of the next baffle therebeneath and in so doing a rolling action of the ore is produced thereby thoroughly mixing the ore a plurality of times while passing through the throat 14.

The heated air after passing upwardly through opening 30 is directed by the lowermost dividing wall 27 from the chamber 22, into which it flows from the opening 30, through the passages, formed by the openings 25 and the cavities 26 to the other chamber 22. The air is directed by its dividing wall 27 back into the other chamber 22 in a like manner and so forth until it reaches the upper end of the first mentioned chamber 22 from which it passes through the outlet pipe 55. The ore passing slowly over the baffles 23, as previously described, forms a seal around the passages through which the heated air passes from one to the other of the chambers 22. The heated air heats the ore to thereby cause the mercuric fumes therein to be released into the air and said fumes are conveyed with the air out through the pipe 55 to the condensers. The rolling action of the ore, previously described, causes the heat from the air to more readily penetrate the ore. In spite of the fact that the ore is thoroughly dried before entering the throat 14 it will still contain a certain amount of moisture of saturation that can only be eliminated by heat and this moisture will be converted into steam by the heated air in the upper part of the throat 14 and this steam tends to prevent the mercuric fumes from condensing on the cooler ore entering the upper end of the throat. The dried ore continues to flow downwardly to a point between the burners 33, which constitutes the greatest heat area and where the ore is sufficiently heated to vaporize all mercuric minerals, but not heated sufficiently to fuse or melt any other minerals or rock. The extent of the heat at this point, must necessarily be determined by the nature of the ore being treated.

The roasted ore after passing the lowest baffle 23 flows through opening 29 and into the upper hopper 40 and then successively through the hoppers 40 passing in fine streams through their slotted passages 39. The hoppers 40 form "scrubbing hoppers" to scrub out any mercuric fumes that may be left in the roasted ore which fumes would be picked up by the air passing on the outer sides of the baffles 38. The hoppers 40 are also superheated by the roasted ore so that their baffles 38 increase the heat of the air passing therearound to superheat the air sufficiently

to reduce any mercuric ores that it may contact and to thereby make use of waste heat from the roasted ore.

From the foregoing it will be readily apparent that the mercuric fumes are removed from the ore by the heated air and conveyed to the outlet pipe 55 without coming in contact with the gases contained in the products of combustion from the burners 33. Consequently, the carbon monoxide gases of these products of combustion do not come into contact with the mercuric fumes as they are conveyed separately from the furnace through the flues 35 and the flues outlets 31, as previously described.

Obviously, the capacity of the furnace could be increased by providing a plurality of throats, as indicated at 14' in Figure 5, each of which would be of the same construction as the throat 14. If the furnace were provided with two throats 14', as seen in Figure 5, it would have to be widened so that the throats could be disposed in side by side relationship, and in order to heat the adjacent sides 18' of the throats 14', an additional pair of burners 33' would be provided and mounted to discharge into openings 34a in the walls 48'. The openings 34a communicate with space 35a, between the adjacent walls 18', and such space forms an additional fire box and flue, so that both sides 18' of both throats 14' will be heated, as the outer sides 18' will be heated in the usual way by burners 33' through openings 34' which communicate with the spaces 35' which form fire boxes and flues similar to the spaces 35. It will be readily apparent that separate hoppers 40 and heaters 43 could be provided for the two throats 14' or both throats could discharge into a single set of hoppers 40 and a single heater 43 be used with the heated air from one of the pipes thereof being discharged into one of the throats and the heated air from the other of said pipes being discharged into the other throat.

From the foregoing it will be apparent that the applicant's furnace is designed for roasting only fine ores, dust, soot and condenser residue of other types of mercuric furnaces, and by having much more finely crushed ore, than can be treated in other furnaces, the vapor saturation that is lost with coarser ore furnaces can be recovered. The applicant's furnace can function with more finely ground ore because it is built to muffle all flame and combustion from the burners so that there will be no draft from the furnace on the ore and therefore nothing to agitate the finely ground ore to produce dust which would be carried off by the air to the condensers. The amount of oxygen required for oxidation is regulated by the damper 45 and can thus be regulated to conform to the rate of flow of the ore, which in turn is governed by the speed at which the conveyor 54 is driven.

Various modifications and changes are contemplated and may obviously be resorted to as only a preferred embodiment of the invention has been disclosed.

I claim as my invention:

1. An ore reduction furnace comprising an elongated, substantially upright furnace casing, a throat extending downwardly to a point adjacent the bottom thereof, a portion of said throat being adapted to form a passage for finely ground ore which is adapted to flow downwardly there-through by gravity, inverted V-shaped baffle members disposed one above another in said throat and over both sides of which the ore is

adapted to flow, passages having portions formed by said baffle members adapted to convey heated air by a circuitous route back and forth, through said throat and in an upward direction exteriorly of the portion of the throat through which the ore passes, and heating means disposed in the furnace and on the outer side of said throat for heating the ore and air passing therethrough, said furnace comprising spaced superposed hoppers arranged below said throat for receiving the ore therefrom and through which the ore successively passes, and means for conveying the heated air back and forth around the outer sides of said hoppers.

2. A furnace comprising an elongated hollow shaft like furnace casing, a throat member extending through a portion thereof and through which finely ground ore is adapted to be conveyed by gravity, means for restricting the discharge of the ore from the furnace for controlling the flow of the ore through the throat, superposed baffle means disposed in the throat and over which the ore passes in its movement therethrough, means for heating the outer side of said throat for heating the ore passing therethrough, and means for conveying air circuitously back and forth through the baffles for carrying off gases released from the ore by the heating thereof for separating the gases from the ore.

3. A furnace as in claim 2, said baffles each being of inverted V-shape in cross section and being disposed in substantially the same vertical plane, and said throat having substantially parallel sides adjacent to which the lower edges of the baffles are disposed to provide narrow passages through which the ore must pass.

4. A mercuric ore reduction furnace comprising an elongated, substantially perpendicularly disposed furnace casing having a bore disposed to extend substantially from end to end therethrough, a throat member disposed longitudinally of said bore and through which finely ground mercuric ore is adapted to pass by gravity, said

throat being oval shaped in cross section and being provided with wall portions extending longitudinally thereof and disposed adjacent its edges, and forming elongated, substantially perpendicular spaces in the edge portions of the throat, superposed arch shaped members arranged in the central portion of the throat and connected to said walls and forming baffles over which the ore is adapted to flow in relatively thin streams, said walls being provided with opposed openings connecting said spaces with the interiors of said arch shaped members, said openings and the interiors of said arch shaped members forming passages between the spaces, and said spaces being provided with spaced staggeredly arranged transverse walls adapted to form baffles whereby heated air will be directed circuitously back and forth through the arch shaped members so that the mercuric fumes, contained in the ore, are picked up by the heated air passing therethrough, and means for admitting the air at the lower end of said throat and for releasing the air from the furnace at the upper end of the throat.

5. A furnace as in claim 4, the sides of said throat being spaced from the walls of the furnace casing, heating means disposed in the spaces thus formed for heating the throat for heating the ore and air passing therethrough, and said last mentioned spaces forming flues for carrying off the products of combustion from the heating means.

6. A furnace as in claim 4, comprising a bin adapted to receive the ore from the lower end of the throat, and a passage leading from said bin and provided with a driven conveyor for conveying the ore from the bin and for limiting thereby the flow of ore through the throat.

7. A furnace as in claim 4, comprising a hot air heater disposed in said furnace casing and beneath the lower end of said throat for initially heating the air to be conveyed through the throat.

FRANK DUNCAN.
